UNITED STATES PATENT OFFICE.

JAMES PAULL AND ALBERT R. GROTZ, OF WELLSBURG, WEST VIRGINIA.

DESIGN FOR A GLASS RECEPTACLE.

No. 37,570.

Specification for Design.

Patented Oct. 10, 1905.

Application filed August 9, 1905. Serial No. 273,483. Term of patent 14 years.

To all whom it may concern:

Be it known that we, JAMES PAULL and ALBERT R. GROTZ, of Wellsburg, Brooke county, West Virginia, have invented a new, original, and ornamental Design for a Glass Receptacle, reference being had to the accompanying drawings, forming part of this specification, in which—

Figure 1 is a side elevation of a glass receptacle having our ornamental design, and Fig. 2 is a top plan view of the same.

We claim—
The ornamental design for a glass receptacle, as shown.

JAMES PAULL.
ALBERT R. GROTZ.
